SEALED DISPENSER

Frederick G. Lodes, Yonkers, N. Y., assignor to
 Allied Chemical & Dye Corporation, New York,
 N. Y., a corporation of New York

Application February 19, 1949, Serial No. 978

Term of patent 14 years

(Cl. D62—2)

To all whom it may concern:

Be it known that I, Frederick G. Lodes, a citizen of the United States of America, residing at Yonkers, in the county of Westchester and State of New York, have invented a new, original, and ornamental Design for a Sealed Dispenser, of which the following is a specification, reference being had to the accompanying drawing, forming part thereof.

In the drawing:

Fig. 1 is a top plan view of a sealed dispenser, showing my new design.

Fig. 2 is a side elevational view looking in the direction of arrow 2 of Fig. 1.

Figure 3 is a front elevational view looking in the direction of the arrows 3 of Figs. 1 and 2.

Fig. 4 is a rear elevational view looking in the direction of the arrows 4 of Figs. 1 and 2.

Figs. 3 and 4 are shown fragmentarily for convenience in illustration.

I claim:

The ornamental design for a sealed dispenser, substantially as shown.

FREDERICK G. LODES.
